UNITED STATES PATENT OFFICE.

NEWMAN H. HOLLAND, OF WEST ORANGE, NEW JERSEY, ASSIGNOR TO NEW JERSEY PATENT COMPANY, OF WEST ORANGE, NEW JERSEY, A CORPORATION OF NEW JERSEY.

CONTROLLING DEVICE.

1,272,261.

Specification of Letters Patent.

Patented July 9, 1918.

Application filed October 23, 1914. Serial No. 868,153.

To all whom it may concern:

Be it known that I, NEWMAN H. HOLLAND, a subject of the King of Great Britain, and a resident of West Orange, in the county 5 of Essex and State of New Jersey, have invented certain new and useful Improvements in Controlling Devices, of which the following is a description.

My invention relates to controlling devices 10 and especially to controlling devices for business or other phonographs, being in some aspects an improvement on the invention described and claimed in Patent No. 1,106,443 granted August 11, 1914, to Nelson 15 C. Durand and entitled controlling devices.

In the construction disclosed in the patent to Durand, the sound conveyer of the phonograph has applied thereto a device constituting a handle, which is provided with a 20 member movable with respect thereto for effecting the starting and stopping of the phonograph mechanism. This member is normally biased to a position for effecting the stopping of the phonograph mechanism, 25 and, in order to effect the starting of the latter, is moved from such position by the application of pressure thereto by the hand of the operator. It is necessary for the operator to maintain the pressure on this member 30 during the entire time it is desired to continuously operate the phonograph mechanism, and when this time is of considerable duration, as is frequently the case, the maintenance of this pressure becomes tiresome to 35 the operator. Moreover, there is an inclination on the part of some operators, after applying to the movable member the pressure necessary to effect the starting of the phonograph mechanism, to immediately remove 40 this pressure, whereupon the said member will at once return to its normal position and thereby effect the stopping of the phonograph mechanism at a time when it is intended the same should be operating.

45 The principal object of my invention is to provide a construction wherein these objectionable features will be obviated. In conformity with this object, I provide a controlling device of the type above described 50 with simple and improved means whereby when the member for effecting the starting and stopping of the phonograph mechanism has been moved by the application of pressure thereto, to the position for effecting 55 the starting of the phonograph mechanism,

it will be automatically locked in such position to prevent the stopping of the phonograph mechanism after the removal of such pressure. The improved locking means is preferably so arranged that it may be readily operated to release the movable member, to thereby effect the stopping of the phonograph mechanism, by the hand of the operator grasping the device provided with the movable member and constituting the handle for the sound conveyer of the phonograph.

Other objects and features of my invention reside in the details of construction and combinations of elements hereinafter more 70 fully described and claimed.

In order that my invention may be more clearly understood, attention is directed to the accompanying drawing, forming a part of this specification, in which the same reference characters are used to designate corresponding parts throughout and in which—

Figure 1 is a perspective view, partly broken away, of a phonograph with my invention applied thereto;

Fig. 2 is an enlarged longitudinal sectional view, partly in elevation, of the device provided with the movable member for effecting the starting and stopping of the phonograph mechanism and the improved locking means 85 coöperating with such member, the parts being shown in position for effecting the stopping of the phonograph mechanism; and

Fig. 3 is an enlarged part sectional view of the outer end portion of the device as 90 shown in Fig. 2 but with the parts thereof in position for effecting the starting of the phonograph mechanism.

Referring to the drawing, reference character 1 designates a phonograph comprising 95 the phonograph mechanism 2 and the driving mechanism 3. The phonograph mechanism is adapted to be driven from the driving mechanism through a clutch comprising a shiftable clutch member 4, movement of 100 which in opposite directions serves to respectively connect and disconnect such mechanisms.

The phonograph mechanism comprises a mandrel 5 for carrying the record or record 105 blank 6 and the usual carrier arm (not shown) on which the recorder 7 and reproducer 8 are so mounted that either is adapted to be brought into operative position with respect to the mandrel and the record or 110

blank carried thereby. Reference character 9 represents a sound conveyer, the inner end of which is adapted to be slipped over the neck of either the recorder or the reproducer. The sound conveyer is flexible for the greater portion of its length, but the outer end portion thereof is preferably rigid and terminates in a mouth-piece 10. Movement of the clutch member 4 to connect and disconnect the driving and phonograph mechanisms is controlled by means preferably comprising a bell crank lever 11, pivotally mounted on the frame of the phonograph and having a loose connection with the clutch member 4, a pneumatic device, and suitable connecting mechanism 12 between the bell crank lever and the pneumatic device. The pneumatic device consists of a pump 13 mounted on the frame of the phonograph, another pump 14, and a flexible tube 15 connecting these pumps. The piston 16 of pump 13 is suitably connected to mechanism 12, and is movable to actuate this mechanism, and thereby bell crank lever 11 and clutch member 4, by changes of pressure in the column of air in the tube 15. The pump 14 comprises a hollow cylindrical casing 17 and a piston 20 disposed in the latter; the casing being provided at one end 30 with a nipple 18 for connection with the tube 15 and at its other end with a removable cap 19, and the piston being secured to a rod 21 which extends through the cap 19 and has a button 22 on its outer end. A spiral spring 23, disposed between the end of casing 17 connected with tube 15, or the inner end thereof, and the piston 20, constantly tends to force the latter toward the opposite or outer end of this casing. The outer end portion of rod 21 is reduced to 40 form a shoulder 26 which coöperates with cap 19 to limit the outward movement of the piston 20.

A bracket 24 is suitably secured at its ends 45 to the pump casing 17, the major portion of this bracket being spaced from the casing and having secured thereto a pair of spring clips 25 which are sprung over the rigid outer end portion of the sound conveyer 9, whereby the pump 14 will be secured to the sound conveyer in spaced relation thereto and serve as a handle therefor. The construction and size of the pump 14 are such as to enable the operator to readily 55 grasp the same in his hand and at the same time permit him to actuate the button 22 by his thumb, as clearly shown in Fig. 1.

It will be obvious that on applying sufficient pressure to the button 22 to depress rod 21, piston 20 will be forced inwardly 60 against the action of spring 23 and, by means of the column of air in tube 15, the pump 13, connecting mechanism 12, and bell crank lever 11, the clutch member 4 will be shifted to operatively connect the phono-

graph mechanism 2 with the driving mechanism 3; and that when this pressure is removed and spring 23 is free to act, the piston 20 will be forced outwardly in casing 17 and the clutch member 4 will be shifted in the 70 opposite direction to disconnect the phonograph and driving mechanisms 2 and 3.

In the absence of means other than that referred to in the above detailed description, it is evident that it will be necessary for the 75 operator to keep the rod 21 depressed against the action of spring 23, by maintaining pressure on button 22, as long as it is desired to keep the phonograph mechanism operating. In order to obviate this necessity, I have 80 provided the pump 14 with means for automatically holding or locking the rod 21 in depressed position, to thereby prevent the disconnection of the driving and phonograph mechanisms, until such means is operated to release this rod. This locking means preferably comprises a small resilient rod 27 secured at one end to the piston or plunger 20 and extending outwardly through a slot 28 in the cap 19. The outer end portion of rod 27 is disposed loosely in a small notch 29 formed in the outer portion of button 22. The rod 27 is cut away or notched near its outer end and on the side thereof adjacent rod 21, as indicated at 30, whereby 95 the same is provided with a shoulder 31. At its outer end the rod 27 is provided with a small curved portion or lug 32 which projects slightly above the button 22 and extends outwardly from the center of the latter. In order that rod 27 may be readily flexed by a slight outward pressure on its upper end, the rod is formed with a reduced portion 33.

Rod 27, under its own resiliency, normally 105 tends to assume a position substantially parallel to the piston rod 21 and in engagement with the inner wall of the slot 29 in button 22. When the parts of the pump 14 are in position for effecting the stopping of the phonograph mechanism, however, the inner wall of slot 28 in cap 19 bears against rod 27 and flexes or bends the same away from rod 21, as clearly shown in Fig. 2. Upon pushing rod 21 inwardly, as by applying pressure to button 22 by the thumb, to thereby effect the starting of the phonograph mechanism, the rod 27, after the shoulder 31 thereof moves past cap 19, will spring inwardly toward rod 21 and its shoulder will engage the inner side of cap 19 to lock the parts of the pump in position for maintaining the phonograph mechanism in operation, as shown in Fig. 3. In order to release rod 21 and piston 20 to thereby effect the 110 stopping of the phonograph mechanism, it is merely necessary to apply sufficient outward pressure to rod 27 to disengage the shoulder 31 thereof from cap 19. This may be readily accomplished by pressing the 115 120 125 130

thumb outwardly against or over the lug or outer curved end 32 of this rod.

While I have specifically described the preferred embodiment of my invention, it is to be understood that I am not limited to such embodiment, but that the same is subject to many changes and modifications in the form, size, and arrangement of parts without departing from the spirit of the invention. It is obvious, for example, that my invention is not limited to a pneumatic controlling device.

Having now described my invention, what I claim as new and desire to protect by Letters Patent of the United States is as follows:

1. In a device of the character described, means adapted to control operating mechanism comprising a tubular member containing an element operable to effect the operation of said mechanism, said element being normally biased to inoperative position, and a resilient device carried by said element and adapted to coact directly with said member to lock said element in operative position, substantially as described.

2. In a device of the character described, means adapted to control operating mechanism comprising a hollow member containing a spring pressed element operable to effect the operation of said mechanism but normally tending to assume inoperative position, and a resilient rod carried by said element and coacting directly with said hollow member to automatically lock the spring pressed element in operative position, substantially as described.

3. In a device of the character described, means adapted to control operating mechanism comprising a member adapted to be held in the hand, an element operable by the thumb, when said member is held in the hand, to effect the operation of said operating mechanism, said element being biased to inoperative position, and a device applied to said element for locking the latter in operative position, said device being main-

tained in inoperative position by said member when said element is in inoperative position, substantially as described.

4. In a device of the character described, means adapted to control operating mechanism comprising a member adapted to be held in the hand, an element operable by the thumb, when said member is held in the hand, to effect the operation of said operating mechanism, said element being biased to inoperative position, and a device applied to said element and adapted to coact directly with said member to automatically lock said element in operative position, substantially as described.

5. In a device of the character described, means adapted to control operating mechanism comprising a member adapted to be held in the hand, an element operable by the thumb, when said member is held in the hand, to effect the operation of said operating mechanism, said element being biased to inoperative position, and a device applied to said element for locking the latter in operative position, said device being normally held in inoperative position by said member and being operable by the thumb to release said element, substantially as described.

6. In a device of the character described, means adapted to control operating mechanism comprising a hollow member adapted to be held in the hand and containing an element movable therein by the thumb to effect the operation of said operating mechanism, said element being biased to inoperative position, and a device applied to said movable element for automatically locking the latter in operative position, said device being normally held in inoperative position by said member, substantially as described.

This specification signed and witnessed this 22nd day of October, 1914.
